DESIGN FOR A TOOTHPICK

Elmer L. Johnson, Minneapolis, Minn.

Application September 7, 1946, Serial No. 133,166

Term of patent 3½ years

(Cl. D86—10)

To all whom it may concern:

Be it known that I, Elmer L. Johnson, a citizen of the United States, residing at Minneapolis, county of Hennepin and State of Minnesota, have invented a new, original, and ornamental Design for a Toothpick, of which the following is a specification, reference being had to the accompanying drawing, forming part thereof, and in which

Figure 1 is a view showing one side of a toothpick embodying my new design;

Figure 2 is a view showing the opposite side thereof; and

Figure 3 is a top view of the toothpick shown in Fig. 1.

I claim:

The ornamental design for a toothpick, substantially as shown.

ELMER L. JOHNSON.
